CONTROL APPARATUS

Walter J. Podbielniak, Chicago, Ill.

Application July 21, 1934, Serial No. 736,328

13 Claims. (Cl. 202—160)

The present invention relates to improvements in control apparatus suitable for various purposes, for example, in fractional distillation. This application is a continuation in part of my prior application Serial No. 572,146, filed October 30, 1931, Patent No. 1,967,258, July 24, 1934.

The present invention will be fully understood from the following specification, illustrated by the accompanying drawings, in which:

10 Figure 1 is a general view, partly in elevation and partly in section, and largely diagrammatic without reference to scale, of a layout of apparatus suitable for carrying the invention into effect;

15 Fig. 2 is a detail view, partly in section of the mechanism provided for the control of a valve or other suitable operating mechanism; and

Fig. 3 is a detail plan view of a part of the control mechanism shown in Fig. 2.

20 Referring more particularly to Fig. 1, the numeral 31 indicates the conduit to which a selected gas or vapor supplied to the system to which the control apparatus of the present invention may be supplied. The selected gas may be derived 25 from a fractional distillation apparatus, for example, an apparatus of the analytical type as described in my prior applications Serial No. 351,726, filed April 1, 1929, Patent No. 2,009,814, July 30, 1935 and Serial No. 475,585, filed August 30 15, 1930, Patent No. 1,917,272, July 11, 1933 and my application Serial No. 572,146, Patent No. 1,967,258, hereinbefore referred to. As is readily apparent, the gas or fluid reaching the conduit 31 may be derived from any other suitable source.

35 In the embodiment of the invention illustrated, the line 31 extends to the control valve 33, the construction and operation of which will be more fully hereinafter set forth. From the control valve 33, vapors from the distillation column are 40 conducted through the line 37 to the receiving bottle or container 38, in which, as described in the prior applications hereinbefore referred to, a reduced pressure is maintained and a temperature such that the contents thereof are kept in 45 vapor form. The receiving container 38 is of fixed volume and the increase in pressure therein resulting from the receipt therein of vapors evolved from the distillation column is indicated by providing from the line 37 a connection 39 leading to a manometer 40, by which the pressure in the receiving container 38 is indicated and a further control of the operation secured, as more 50 fully hereinafter set forth.

A desired initial pressure, either above or below 55 atmospheric may be secured in the line 37 and

container 38 through valved line 41, which may be connected to a compressor or vacuum pump, as desired.

The numeral 66 represents a recording pyrometer, suitably of the potentiometer type, operated through connectors 65 and 65a from a thermocouple or other suitable means, provided in any desired portion of the system subject to control, for example, in some part of the distillation apparatus in the embodiment of the invention illustrated, and more fully set forth in my prior application Serial No. 572,146 hereinbefore referred to. The recording arm of the pyrometer is indicated by the numeral 67. As such pyrometers are of a type well known in the art, the detailed mechanism thereof is not shown. As is usual in such pyrometers, the recording arm 67, by which a record is made upon a traveling paper sheet 68 is operated by a shaft 69 and is caused to move to the left or clockwise with rise in temperature.

20 In the operation of such recording pyrometers, it has hitherto been customary to cause the paper sheet 68 upon which the record is made to be moved by clock-work so as to travel at a constant rate of speed, so that the record made indicates not only the temperature of the device under operation, but also the time at which the record is made. In accordance with the present invention, however, I provide means whereby the feed of the paper sheet 68 may be controlled in accordance with other factors, such as the quantity of the vapor passing over, through the pressure rise in the fixed-volume container 38, in which the vapor fractions from a distillation are received and maintained in vapor phase. As a result, a record may be made upon the sheet 68, showing the temperature of evolution of the successive vapor fractions in relation to their amount, providing at once an analytical distillation curve of the material under treatment. Means suitable for this purpose are shown on the drawing in Fig. 1 and details thereof in Figs. 2 and 3.

30 As hereinbefore set forth, a pressure sensitive device or manometer 40 is provided in direct communication with the vapor line 37 leading to the receiver 38. This may suitably be a U-tube manometer, having a closed leg 40a communicating with the evacuated receiver 38 and an open leg 40b, and containing a column of mercury or other suitable conductive liquid which is connected 40 through a conductor 70 with one pole of a suitable source of electricity.

35 As successive increments of vapor pass from the distillation column into the receiver 38, they cause a corresponding increase in pressure there-

55

in, the contents of the receiver being maintained at a substantially constant temperature and in vapor phase. These increments of pressure are made to cause a corresponding feed of the paper record sheet 68 of the pyrometer 66, for example, in the following manner.

The paper feed roll of the pyrometer is mounted upon a drive shaft 74 which is driven through suitable reduction gears 75 from the shaft 76 of motor 77. On the shaft 74 there is likewise mounted, exteriorly of the pyrometer 66, a pair of soft rubber rolls 78, of which only one is shown, this mechanism being shown in greater detail in my prior applications above referred to. Extending into the open leg 40b of the manometer 40, there is provided an elongated metallic contact rod 81, the end of which is, in its normal position, but a very slight distance above the mercury column, say 0.1 mm. The rod 81 extends vertically upward and passes between the rubber rolls 78 so that, when the motor 77 is driven to operate the shaft 74 and move the paper sheet 68 of the recording pyrometer, the rubber rolls 78 are driven to raise the contact rod 81. As the distillation proceeds, and vapor is permitted to pass from the distillation column through the lines 31 and 37 into the receiver 38 and increases the pressure therein, in proportion to the amount of vapor entering the receiver, the increase in pressure is communicated through the line 39 to the manometer 40. The mercury is thereby caused to rise in the leg 40b of the manometer and contact with the rod 81, whereupon a circuit is closed through the mercury, the contact rod 81, the connector 82, the motor 77, and the connector 83 to the opposite pole of the source of current supply. The motor 77 is thereby energized to operate the shaft 74 and the feed roll 71 for the paper sheet 68 of the recorder. In doing so, through the movement of the rubber rolls 78, the contact rod 81 is raised and as soon as it breaks contact with the mercury in the manometer, the circuit through the motor 77 is broken and operation thereof ceases. At the same time that the movement of the paper sheet 68 has been effected in this manner, the recording arm 67 of the pyrometer has been operated to indicate upon the paper sheet the temperature at the selected point. The paper sheet 68 is thereby made to bear a record showing, by movement of the recording pen transversely of the sheet, the said temperatures and by markings longitudinally of the sheet, the quantity of fractions or vapors entering chamber 38.

In conducting operations such as distillations, it is sometimes desirable that the rate of distillation or of flow of fluids should vary, being greater during one period, such as the distillation of a pure or relatively pure component, during which period the control temperature remains substantially constant, and being reduced when the temperature varies, as in transition from one component to another, the reduction in rate of distillation being desirably proportioned to the rate of change of temperature. Considered from the standpoint of a distillation curve, for example, the rate of distillation should be regulated so as to be inversely proportional to the slope or tangent of the fractional distillation curve. In the drawings, means are shown whereby such control can be secured.

In the operation in accordance with the present invention, the rate of flow through line 31 is controlled by the valve 33 between the vapor

line 31 leading from the top of the column and the line 37 leading to the lower pressure receiver 38. As shown more particularly in Fig. 2, the valve member 33 may consist of a casing 88 into which the vapor line 31 leads, and with an outlet 89 to which the line 37 is connected. Within the casing 88, a suitable valve seat 90 is provided at the inner opening of the outlet 89, on which seats the needle valve 91 mounted on a reciprocable valve stem 92 which projects through the back of the casing and is operated by the lever 93. To avoid leakage, a metallic bellows diaphragm 94 surrounds the valve stem 92 and is securely attached at one end to the back of the casing 88 and at the other to the valve stem. 15

Suitable means are provided for controlling the movement of the valve 91 as a function of the change in temperature at the selected point, such as the outlet of the distillation column, the quantity of vapor received in the receiver 38 or both. 20

As pointed out hereinbefore, temperature changes at the selected point are communicated through the usual thermocouple connections to the recorder arm 67 on shaft 69 of the pyrometer 66. The shaft 69 carries, at the back of the instrument, as shown more particularly in Fig. 3, an arm 95, at the end of which is mounted the rotatable pin 96 carrying a spring-pressed pawl 97. The pawl 97 engages a ratchet wheel 98 rotatably mounted on an arbor 99 carried in a suitable bearing on the support 100. At a slight distance from the ratchet wheel 98 and in a parallel plane with respect thereto, there is provided a worm wheel 101 mounted on an arbor 102 coaxial with the arbor 99 of the ratchet wheel 98. 30 The arbor 102 is mounted in a suitable bearing on the support 103. Contact arms 104 and 105 are mounted on the ratchet wheel 98 and the worm wheel 101 respectively, these contact arms being normally spaced from each other, but being 40 adapted to engage on movement of the ratchet wheel 98. On the outer sides of the ratchet wheel 98 and worm wheel 101, the spring contacts 106 and 107 respectively are provided, for an electrical connection as hereinafter pointed out. 45

The worm wheel 101 meshes with and is driven by a worm 108 on a shaft 109 which is driven through suitable reduction gears 110 from motor 111. The shaft 109 extends through a sleeve cap 112 provided with a constricted portion 113, and extends through the cylindrical casing 114 of the actuating or tangent-control member, generally designated by the numeral 115. The cylinder 114, which is threaded at one end into the sleeve cap 112, is provided at its opposite end with a reduced extension 116 provided internally with a bore 117 into which the shaft 109 projects. The reduced portion 116 is extended as a cylindrical shaft member 118 which passes through a bearing 119 in a suitable support member 120. Within the cylindrical casing 114 of the actuating member 115, there is fixed to the shaft member 109 an externally screw-threaded collar 121, the threads of which mate with threads 122 formed internally of the cylindrical casing 114. The actuating or control member and its shaft extension 118 are axially movable with respect to shaft 109 and bearing 119. 60

The shaft extension 118 of the cylindrical casing 114 of the actuating mechanism 115 is provided at its outer end with a pulley 123 which is driven from a pulley 124 mounted on a shaft 124a forming a part of the shaft of motor 77. 70

On rise in temperature at the control point, the recorder arm 67 of the pyrometer 66 is moved 75

clockwise. This movement is imparted through the shaft 69 to the arm 95 carrying the pawl 97, which is spring-pressed against the ratchet wheel 98. As a result, on rise in temperature in the column, the ratchet wheel 98 is caused to move, and the contact arm 104 is thereby brought into contact with the contact arm 105 on the worm wheel 101. When this takes place a circuit is closed from one pole of a source of current through connector 125, arm 106, ratchet wheel 98, contact arms 104 and 105, worm wheel 101, contact 107, connector 126, motor 111 and connector 127 to the opposite pole of the current source. The motor 111 is thereby energized and rotates the shaft 109. The rotation of the shaft 109 is communicated through the threaded collar 121 to the cylindrical casing 114 of the actuating mechanism 115, thereby causing axial movement of the latter which in turn is communicated to the forked end 128 of lever 93 (which embraces the constricted portion 113 of the sleeve cap 112), thereby tending to move the needle valve 91 toward its seat and reduce or close the opening between the vapor line 31 and the line 37 leading to the receiver 38. At the same time, the movement of the shaft 109, acting through the worm 108, rotates the worm wheel 101, thereby separating the contacts 105 and 104 and breaking the hereinbefore described circuit to the motor 111. In the event of further rise in temperature, the operation is repeated.

The means shown in the drawings are designed so that a drop in temperature will have no effect.

The actuating cylinder 115 is likewise affected by the increase in pressure in the vapor receiver 38. As hereinbefore set forth, such increase in pressure, results in a corresponding energizing of the motor 11, from which the paper feed mechanism for the recorder 66 is driven. From the motor shaft extension 124a of the motor 11, drive pulley 124 causes corresponding movement of a pulley 123 on the shaft extension 118 of the actuating cylinder 115, causing it to rotate in such manner that if, at the time, the threaded collar 121 within the actuating cylinder is stationary, the axial movement of the actuating cylinder tends to open the valve and increase the rate of distillation. As hereinbefore described in connection with the recording mechanism, this same operation of motor 11 causes movement of contact rod 81, which breaks the current controlling motor 11. On further rise in pressure in receiver 38, the operation is repeated.

It will be clear from the above description of the operation of the actuating cylinder 115 or the operating lever 93 of the control valve 33 that it is individually responsive to the changes in pressure and of temperature at the control point, and mechanically compounds the effects due to both of these causes. As a result of proper selection of gear ratios, screw pitches and the like, the relative effect of each of these elements controlling the cylinder 115 and its movement may be modified, although, it is preferred in the case of control of a distillation process that its response be so controlled as to correspond substantially and sensitively to changes in the tangent or slope of the distillation curve.

Although the present invention has been described in connection with the details of specific method and apparatus embodying the same, it is not intended that these details shall be regarded as limitations upon the scope of the invention, except in so far as included in the accompanying claims.

I claim:

1. In combination, distillation control means and operating means therefor responsive to temperature and pressure changes, said operating means comprising interconnected rotatable members, and means for rotating one of said members in response to pressure changes and means for rotating the other of said members in response to temperature changes.

2. In combination, distillation control means and operating means therefor, said operating means comprising an axially-movable rotatable cylindrical casing member, a rotatable member entering said casing and internally engaged therewith, and means for rotating one of said members including a pressure-responsive device, and means for rotating the other of said member, including a temperature-responsive device.

3. In combination, distillation control means and operating means therefor, said operating means including an axially-movable, rotatable cylindrical casing, said casing having an internal screw-threaded portion, means for rotating said casing, a rotatable shaft entering said casing and bearing a threaded member engaging the internally threaded portion of said casing, and means for rotating said shaft.

4. In combination, distillation control means and operating means therefor, said operating means including an axially-movable, rotatable cylindrical casing, said casing having an internal screw-threaded portion, means for rotating said casing, a rotatable shaft entering said casing and bearing a threaded member engaging the internally threaded portion of said casing, and means for rotating said shaft, and means operable on rotation of said casing to render said casing-rotating means inoperative.

5. In combination, distillation control means and operating means therefor, said operating means including an axially-movable, rotatable cylindrical casing, said casing having an internal screw-threaded portion, means for rotating said casing, a rotatable shaft entering said casing and bearing a threaded member engaging the internally threaded portion of said casing, and means for rotating said shaft, and means operable on rotation of said shaft to render said shaft-rotating means inoperative.

6. In combination, distillation control means and operating means therefor, said operating means comprising a control lever, an axially-movable, rotatable cylindrical casing engaging said lever, said casing having an internally-threaded portion, a rotatable shaft entering said casing, a threaded member mounted on said shaft and engaging the internally-threaded portion of said casing, said threaded member being longitudinally fixed with respect to said casing, and independently controlled means for rotating the casing and the threaded member, whereby a resultant movement is imparted to said casing and to said lever.

7. In combination, distillation control means operable in response to the temperature of vapors issuing from a distillation column and operating means therefor, means for actuating said control means, said actuating means comprising a rotatable member, a shaft carrying said rotatable member, motor means for driving said shaft, a normally open electrical control circuit for said motor, a rotatable disk, a contact for said circuit carried by said disk, a second rotatable disk spaced from the first mentioned disk, a contact for said circuit carried by the second disk, tem-

- perature-responsive means for imparting movement to the first disk, thereby causing the contacts to engage to close said control circuit and energize the motor, thereby rotating said shaft and rotatable member, and means carried by said shaft to rotate the second disk and move the second contact member out of engagement with the first contact member, thereby opening said control circuit and de-energizing the motor.
8. In combination, distillation control means operable in response to the temperature of vapors issuing from a distillation column and operating means therefor, means for actuating said control means, said actuating means comprising a rotatable member, a shaft carrying said rotatable member, motor means for driving said shaft, a normally open electrical control circuit for said motor, a rotatable ratchet wheel, a contact for said electrical circuit carried thereby, a member actuated in response to temperature changes, an arm carried thereby, a pawl on said arm engaging said ratchet wheel to impart movement thereto, a worm wheel spaced from said ratchet wheel and carrying a second contact for said electric circuit, whereby on movement of the ratchet wheel, the contact thereon engages said second contact to close said control circuit and energize the motor, thereby rotating said shaft and rotatable member, and a worm gear carried on rotation of the shaft, said worm wheel is moved to disengage said second contact and break said control circuit, thereby de-energizing said motor.
9. In combination, a controlled element and control means therefor, said means comprising an axially-movable rotatable cylindrical casing, a rotatable member entering said casing and internally engaged therewith, and means for rotating the casing independently of said rotatable member, including a pressure-responsive device, and means for rotating the rotatable member independently of said casing, including a temperature-responsive device.
10. In combination, a controlled element and control means therefor, said means comprising an axially-movable, rotatable cylindrical casing, said casing having an internal screw-threaded portion, means for rotating said casing, a rotatable shaft entering said casing and bearing a threaded member engaging the internally threaded portion of said casing, means for rotating said shaft, and means operable on rotation of said casing to render said casing-rotating means inoperative, said casing being rotated independently of said shaft and said shaft being rotated independently of said casing.
11. In combination, a controlled element and control means therefor, said means comprising an axially-movable, rotatable cylindrical casing, said casing having an internal screw-threaded portion, means for rotating said casing, a rotatable shaft entering said casing and bearing a threaded member engaging the internally threaded portion of said casing, and means for rotating said shaft, and means operable on rotation of said shaft to render said shaft-rotating means inoperative, said casing being rotated independently of said shaft and said shaft being rotated independently of said casing.
12. In combination, a controlled element and control means therefor, said means comprising a rotatable member, a shaft carrying said rotatable member, motor means for driving said shaft, a normally open electrical control circuit for said motor, a rotatable disk, a contact for said circuit carried by said disk, a second rotatable disk spaced from the first mentioned disk, a contact for said circuit carried by the second disk, temperature-responsive means for imparting movement to the first disk, thereby causing the contacts to engage to close said control circuit and energize the motor, thereby rotating said shaft and rotatable member, and means carried by said shaft to rotate the second disk and move the second contact member out of engagement with the first contact member, thereby opening said control circuit and de-energizing the motor.
13. In combination, a controlled element and control means therefor, said means comprising a rotatable member, a shaft carrying said rotatable member, motor means for driving said shaft, a normally open electrical control circuit for said motor, a rotatable ratchet wheel, a contact for said electrical circuit carried thereby, a member actuated in response to temperature changes, an arm carried thereby, a pawl on said arm engaging said ratchet wheel to impart movement thereto, a worm wheel spaced from said ratchet wheel and carrying a second contact for said electric circuit, whereby on movement of the ratchet wheel, the contact thereon engages said second contact to close said control circuit and energize the motor, thereby rotating said shaft and rotatable member, and a worm gear carried on said shaft and engaging said worm wheel whereby, on rotation of the shaft, said worm wheel is moved to disengage said second contact and break said control circuit, thereby de-energizing said motor.

WALTER J. PODBIELNIAK. 55
